ATTORNEY.

UNITED STATES PATENT OFFICE.

GEORGE D. MAYO, OF FRANKLIN, NEW HAMPSHIRE, ASSIGNOR TO THE SULLOWAY MILLS, OF SAME PLACE.

WORK-TRANSFERRING MECHANISM FOR KNITTING-MACHINES.

SPECIFICATION forming part of Letters Patent No. 453,494, dated June 2, 1891.

Application filed August 12, 1890. Serial No. 361,768. (No model.)

To all whom it may concern:

Be it known that I, GEORGE D. MAYO, a citizen of the United States, and a resident of Franklin, county of Merrimac, and State of New Hampshire, have invented certain new and useful Improvements in Work-Transferring Mechanism for Knitting-Machines, of which the following is a specification.

My invention relates to that class of work-transferring mechanisms in which a series of transferring-points projecting from a disk or carrier are in operation mounted above and substantially over the knitting-machine needles with which they are to co-operate, and are successively brought into relation to their appropriate needles to permit of the transfer of the loops carried by them thereto by imparting to their disk or carrier a wabbling movement back and forth across its plane while held from rotation. In work-transferring mechanisms of this class as heretofore constructed the shaft, which supports the disk or carrier at its lower end by a ball-and-socket connection or by a crank or eccentric having an inclined axis, is dependent from the under side of a frame or arm suitably mounted upon the upper side of the bed-plate or knitting-machine table, and the transfer of the loops from the transferring-points to the needles is effected, when these parts are brought into relation, by slipping such loops from the former down upon the latter either by hand or by a transferring-plate or a series of transferring-bits, which two latter are operated from the disk or carrier supporting shaft through suitable connections. These forms of mechanism, while efficient in operation and accomplishing the objects for which they were intended, have been found inconvenient in practice when used in connection with some forms of machine, principally because of the fact that in consequence of the presence of other parts upon the bed-plate or machine-table the application of the frame or arm thereto is rendered extremely difficult if not impossible.

The object of my invention is to obviate this defect and to provide a work-transferring mechanism of the class above specified which shall be supported from the upper end of the needle-cylinder, which shall dispense with the

usual transferring-plates and bits and accomplish the automatic transfer of the loops from the transferring-points to the needles by the action of the transferring-points alone, and which shall permit of the ready removal of the disk or carrier from its supporting-shaft and of its replacement thereon, as the exigencies of the knitting or the occasion may demand.

To these ends the invention consists, first, in the combination, with a suitable block or base adapted to enter and fit the upper end of the needle-cylinder of a knitting-machine, of work-transferring points and co-operative parts mounted thereon, whereby the mechanism may be applied to the upper end of such cylinder and there held or be removed therefrom, as desired; second, in the construction of the transferring-points and in their combination with both their supporting and operating devices and with the knitting-machine needles, whereby they may be brought into relation to their respective needles to permit of the loops carried by them being transferred thereto; third, in the special means made use of for holding the disk or carrier which supports the transferring-points upon its operating crank or eccentric, and, fourth, in various other constructions and combinations of parts, all of which will be hereinafter more fully described.

Referring to the accompanying drawings, which form a part of this specification, Figure 1 is a sectional elevation of the upper portion of a circular-knitting machine with my invention applied in connection therewith, the disk or carrier which supports the transferring-points being shown in central section; Fig. 2, a section of the work-transferring mechanism, taken on the line xx of Fig. 1, looking downward; Fig. 3, a section of the transferring-point disk or carrier-shaft, taken on the line yy , Fig. 1, looking upward; Fig. 4, a front and side elevation, respectively, of one of the work-transferring points detached; and Fig. 5, a detail, looking upward, the section being taken on the line zz .

In all the figures like letters are employed to designate corresponding parts.

A indicates the needle-cylinder, a the needle, and A' the cam-cylinder, of a circular-knitting machine, which, so far as my present

invention extends, are or may be with their co-operating parts of any ordinary or preferred construction and require no further description herein.

5 B indicates the block or base in and upon which the transferring devices are mounted and carried. This block or base in my preferred form of construction is adapted to enter and fit the upper end of the needle-cylinder in connection with which it is to be employed, and may be provided on its periphery with an outwardly-projecting flange b or other equivalent stop, whereby its entrance down into the needle-cylinder beyond a certain distance may be prevented.

10 Journaled in a bearing b' , formed in the block or base B, is a shaft C, the lower portion c of which is preferably reduced in diameter to adapt it to fit therein and afford a shoulder c' to rest upon the upper side of the block or base and maintain the shaft at the same elevation with respect to said side at all times. In addition thereto this shaft is also provided with a turn-button c^2 at its 15 lower end, whereby it may be detachably locked in the bearing b' , and with a crank c^3 or other equivalent means at its upper end, through which its rotation may be effected.

15 Secured to or formed integrally with the shaft C is a crank or eccentric D, which in my preferred form of construction is made tapering in form and arranged upon the shaft with its axis inclined at an angle thereto. In the drawings I have shown this crank or eccentric disposed with its smaller end downward; but it is obvious that the same may be reversed and the larger end arranged in that position without departing from my invention.

20 Mounted upon the crank or eccentric D is the disk or carrier E, which is detachably held thereon by means of the yoke F. This yoke is provided with a circular orifice f , which is slightly larger in diameter than the larger end

25 of the crank or eccentric, and has connecting with it a recess f' , as shown. As thus constructed, the yoke is secured to the upper side of the disk or carrier by means of screws e , which, passing through slots e' in the former, enter suitable holes formed in the latter.

30 When the disk or carrier is applied to the crank or eccentric and the yoke is in the position shown Figs. 1 and 2, the disk or carrier will be secured thereon and held from displacement. When, on the other hand, the yoke 35 is moved so as to bring the orifice f over the disk or eccentric, the disk or carrier may be removed by sliding it down over such crank or eccentric and over the lower end of the shaft C when this latter is detached from its bearing in the block or base B.

To prevent the rotation of the disk or carrier when the parts are assembled and the shaft C is rotated, I provide the stud or post b^2 , which is fixedly secured in and extends upwardly from the block or base B and engages with the slotted lug e^2 , projecting outward from the hub thereof. By these means, as will

be seen, the disk or carrier will be positively restrained from rotation, and the only movement that will be communicated to it by the 70 rotation of the shaft will be the wabbling one back and forth across its plane.

75 Secured to the disk or carrier E so as to depend from its under side and incline slightly inward are the transferring-points g , through which the transfer of the loops of the fabric to the knitting-machine needles is effected. These transferring-points are each provided with its outer side with a longitudinal groove g' , for reception of the needle a when such 80 point is carried over it, and also with a transverse groove g^2 , for receiving and carrying the loop of the fabric when placed therein.

85 As thus constructed, when the transferring mechanism is applied to the knitting-machine, the transferring-points will be supported above the needle-cylinder in the position shown in Fig. 1, and will be successively carried down in rear of their appropriate needles, with their longitudinal grooves g' 90 over the rear upper portions of the same, as illustrated at the right in said figure, by imparting to their disk or carrier a wabbling movement back and forth across its plane, which may be done by rotating the shaft C 95 and with it the crank or eccentric D, upon which the disk or carrier is mounted. The movement of the transferring-points as they are carried down over the rear upper portions of the needles by the wabbling of their 100 disk or carrier also carries down the transverse grooves g^2 over the needle-hooks until they register with their interiors, the effect of which movement is to force the loops carried in these grooves down into the hooks of the 105 needles, where they are securely held as the transferring-points ascend in their further movement, and their transfer thereto is thus accomplished without the aid of other appliances.

110 To secure the transferring-points to their disks or carrier, any of the well-known methods may be adopted. I prefer, however, to provide them with a flattened shank-like portion g^3 , and to secure them by solder or otherwise in suitable grooves formed in the periphery of the carrier, as shown.

115 The parts being constructed and arranged as above set forth, the operation of the mechanism will be as follows: The shaft will first 120 be detached from the block or base, the yoke which holds the disk or carrier in place properly adjusted, and the disk or carrier removed from the crank or eccentric and from the shaft. The loops of the fabric will then be 125 picked upon the transferring-points and carried into the transverse grooves formed therein. The parts of the mechanism will then be reassembled, the block or base adjusted in the upper end of the needle-cylinder, and the crank at the upper end of the shaft 130 revolved. The effect of this revolution of the shaft will be to cause the disk or carrier to wabble back and forth across its plane and

successively carry the transferring-points down into relation to their appropriate needles, forcing the loops carried by their transverse grooves down into the hooks of the 5 needles, and thereby accomplish their transfer thereto.

From the above it will be seen that I produce a work-transferring mechanism which, while simple in construction and efficient in 10 operation, may be applied in connection with any of the various forms of knitting-machines and effect the transfer of the work thereto automatically.

In the foregoing I have described the best 15 means contemplated by me for carrying my invention into practice; but I wish it distinctly understood that I do not limit myself strictly thereto, as it is obvious that I may modify the same in various ways without departing 20 from the spirit thereof.

Again, while I have shown my invention applied in connection with a knitting-machine of the latch-needle class, it is to be understood that it is not applicable to that class of 25 machines alone, but may be employed in connection with some forms of machines of the spring-bearded-needle class and operate with equal efficiency.

Having described my invention, what I 30 claim as new, and desire to secure by Letters Patent of the United States, is—

1. The combination, with a block or base adapted to enter the upper end of a needle-cylinder, a series of transferring-points, and 35 a carrier for such transferring-points, of devices for mounting said carrier upon the block or base and permitting of its operation thereon, substantially as described.

2. The combination, with a block or base 40 adapted to enter and fit the upper end of a needle-cylinder, a series of transferring-points, and a disk or carrier upon which the

transferring-points are supported, of a shaft journaled in said block or base, and a crank or eccentric upon which the disk or carrier is 45 mounted secured to said shaft with its axis inclined at an angle thereto, substantially as described.

3. The combination, with a series of knitting-machine needles and devices for supporting them, a series of transferring-points provided on the outer side of each with both a longitudinal needle-receiving groove and with a transverse loop receiving and carrying groove, and a disk or carrier to which the 55 transferring-points are secured, of devices for supporting the transferring-points above the needles and for imparting to their carrier a wabbling movement back and forth across its plane to successively carry them down in 60 rear and over their appropriate needles to effect the transfer of the loops of the work thereto, substantially as described.

4. The combination, with the disk or carrier provided with the transferring-points, and 65 the crank or eccentric upon which it is mounted, of the yoke provided with the orifice f , having the recess f' communicating therewith, whereby the disk or carrier may be detachably held in position upon the crank 70 or eccentric, substantially as described.

5. The combination, with the block or base B, the disk or carrier E, provided with the slotted lug e^2 , the crank or eccentric D, and the shaft C, upon which it is supported, of the 75 stud or post b^2 , extending upward from the block or base and engaging with the slotted lug, substantially as described.

In testimony whereof I have hereunto set my hand this 7th day of August, 1890.

GEORGE D. MAYO.
